MOVABLE AND ADJUSTABLE PLUMBING
FIXTURE HANGER

Otto Witzleb, Dixon, Ill.

Application July 1, 1931. Serial No. 548,187

4 Claims. (Cl. 248—30)

The invention relates to supporting devices and has for its principal object the provision of a novel hanger structure by means of which plumbing fixtures, such as sinks, washstands, 5 toilets and the like may be installed and securely held against displacement.

An important object of the invention is to provide a hanger device of this character which may be built into the wall itself and which 10 may be of any desired length so as to permit mounting thereon of fixtures of different lengths or types or more than one fixture of the same or different types.

Another object of the invention is to provide 15 a hanger structure of such construction and arrangement as to facilitate the proper positioning of the fixture.

Yet another object is to provide a hanger which though primarily intended for the permanent installation of plumbing fixtures is also 20 capable of use for example in a showroom where it may be desirable to display fixtures attractively to prospective customers.

Another object of the invention is to provide 25 supporting means of this character which is adjustable as to height so as to facilitate leveling up of the fixtures and to permit any desired adjustment in the general elevation at which they are mounted.

20 A more specific object of the invention is to provide a hanger device comprising a stationary horizontal support slidable along which are brackets formed to receive the usual lugs provided at the back of plumbing fixtures for 30 mounting purposes, the movability of the individual brackets along the support making it possible to accommodate different types of fixtures equipped with a varying number of lugs or lugs spaced different distances apart.

An additional object is to provide a device 35 of this character which will be simple and inexpensive to make, easy to install, positive in action, efficient and durable in service, and a general improvement in the art.

To the attainment of the foregoing and other 40 objects and advantages, the invention preferably consists in the details of construction and the arrangement and combination of parts to be hereinafter more fully described and claimed, and illustrated in the accompanying drawings in which:

Figure 1 is a perspective view showing a portion 45 of the studding of a wall and illustrating the stationary support secured thereto,

Figure 2 is a front elevation of the support and a pair of my novel brackets thereon,

Figure 3 is a front elevation of a stationary washstand mounted upon my display device, 60 and

Figure 4 is a vertical section taken on the line 4—4 of Figure 3.

Referring more particularly to the drawings the letter A designates portions of the studding forming part of a wall structure, and B designates the plaster, compoboard or whatever else is used to form the surface.

In carrying out my invention I provide an elongated horizontal supporting member 10 preferably constructed as a suitable length of 70 pipe of any preferred size formed with a longitudinally extending slot 11. This supporting pipe is intended to be mounted permanently upon the studding and to be substantially embedded in the plaster or other surface material 75 and is therefore shown as provided with a plurality of attaching arms 12 lying against the sides of the studding A and secured thereto by means of nails, screws or the like indicated at 13. In actual practice these arms 12 may be 80 connected with the pipe 10 in any desired manner but are preferably welded or brazed thereto. This supporting pipe 10 is mounted at any desired height with respect to the floor of the room where the fixture is to be located and 85 naturally it is logical that this height might vary, depending upon the character of the fixture, that is to say whether it be a sink, lavatory or toilet.

In conjunction with the support 10 I make use 90 of any desired number of brackets indicated as a whole by the numeral 14 and these may be formed in any desired manner but are preferably stamped out of sheet metal of appropriate 95 gauge or thickness. These bracket members 15 are preferably of general rectangular shape with curved lower ends 15 and are formed at their upper ends with outstruck sockets 16 of a size and shape to receive the lugs C commonly provided at the rear of the upper edge of a plumbing fixture such as the washstand illustrated 100 at D.

These brackets are to be mounted upon the support 10 and each is therefore shown as having a pair of spaced vertically elongated slots 105 17 in its intermediate portion, these slots accommodating bolts 18 which pass through the slot 11 in the pipe 10 and which have their heads located within the pipe, the threaded ends of the bolts projecting through the slots 110

17 and carrying washers 19 and nuts 20. Clearly the bolts 18 cooperating with the slots 17 will enable the brackets to be adjusted vertically with respect to the pipe 10. In order that such 5 adjusted position may be positively maintained the brackets are preferably formed at their intermediate portions with horizontally extending corrugations or ridges 21 any selected one of which may be caused to enter the slot 11 so that 10 when the nuts 20 are tightened it will be impossible for the brackets to drop down out of proper position.

In installing the device, the pipe 10 is mounted by means of the arms 12 and the plaster or 15 other surface material B is applied to the studding in such manner that the slotted portion of the pipe will project beyond the surface. If a fixture to be mounted is a relatively short one provided with only two lugs C, then it is 20 necessary to use only two brackets 14 but in the case of many fixtures, like long sinks with integral drain boards there are four or more of such lugs and in such cases it is preferable that a corresponding number of the brackets 25 would be utilized though it might be possible to employ only two, this being immaterial and depending upon the preference of the user. When the nuts 20 are loosened the brackets can of course be shifted individually along the pipe to 30 bring them and consequently the fixture into any desired position. The vertical adjustability of the brackets makes it possible to level up the fixture or change its height with respect to the floor and this would depend upon the character 35 of the fixture displayed, for instance whether it happened to be a kitchen sink, a lavatory or a toilet. As the pipe 10 may be of any indeterminate length it is clear that various different types of fixtures may be supported side by side 40 and any desired distance apart, this latter feature being of particular advantage in case the hanger is used for display purposes as in this way a stock of such goods may be most attractively displayed.

45 From the foregoing description and a study of the drawings it will be apparent that I have thus provided a very simply constructed and inexpensive hanger, support or bracket device for the purpose specified and one which will 50 efficiently perform all the functions for which it is intended. It is thought that the construction, operation and advantages should be readily apparent to one skilled in the art without further explanation.

55 While I have shown and described the preferred embodiment of the invention, it should be understood that the disclosure is merely an exemplification of the principles involved as the right is reserved to make all such changes in 60 the details of construction as will widen the field of utility and increase the adaptability of the device provided such changes constitute no departure from the spirit of the invention or the scope of the claims hereunto appended.

65 Having thus described the invention, I claim:

1. Means for supporting plumbing fixtures

having mounting elements thereon, comprising a slotted stationary horizontal support, a plurality of bracket members mounted against the support, bolts extending through the slot and the bracket members for securing the latter, said 80 bracket members having sockets thereon adapted to receive the mounting elements of the fixtures, said bracket members having vertically elongated slots for the passage of the bolts whereby the bracket members may be adjusted 85 vertically, and other means on the bracket members cooperating with the support for positively maintaining a vertically adjusted position.

2. Means for supporting plumbing fixtures 90 having mounting elements thereon, comprising a slotted stationary horizontal support, a plurality of bracket members mounted against the support, bolts extending through the slot and the bracket members for securing the latter, said bracket members having sockets thereon adapted 95 to receive the mounting elements of the fixtures, said bracket members having vertically elongated slots for the passage of the bolts whereby the bracket members may be adjusted vertically, said bracket members being formed each 100 with a series of projections selectively disposable within the slot of the horizontal support for maintaining a vertically adjusted position to enable the fixture to be leveled.

3. An adjustable bracket structure comprising 105 a horizontal support formed with a longitudinal slot, a bracket member disposed against said support and formed with a vertical slot and also formed with a series of horizontally extending ridges, and a bolt passing through the 110 slot in said support with its head located interiorly thereof and its shank passing through the slot in the bracket member, and a nut on said bolt cooperating with the bracket member to 115 hold the same in vertically adjusted position with a selected one of the ridges received within the slot in the support.

4. An adjustable bracket structure for supporting a plumbing fixture of the type having 120 an upstanding back with depending lugs at the upper portion thereof, comprising a pipe disposable horizontally against a wall and provided with a plurality of laterally extending angularly arranged arms adapted to be secured to the sides of studding forming part of the wall, said pipe being provided with a longitudinally extending slot, bolts extending through said slot and slidably therealong and having their heads disposed within the pipe, members disposed 125 against the pipe and formed with sockets for receiving the lugs on the plumbing fixture, said members being formed with vertically elongated slots slidably adjustably receiving said bolts, and said members being formed at their intermediate 130 portions with ridges any selected one of which may be engaged within the first named slot for the purpose of maintaining vertically 135 adjusted positions of said members for effecting levelling of the fixture.

140 OTTO WITZLEB.
